(57) **CLAIM**

The ornamental design for a remote control, as shown and described.

DESCRIPTION

FIG. 1 is a perspective view illustrating a remote control design according to the present design;

FIG. 2 is a front view thereof;

FIG. 3 is a back thereof;

FIG. 4 is a side view thereof;

FIG. 5 is another side view thereof;

FIG. 6 is a top view thereof; and,

FIG. 7 is a bottom view thereof.

The broken lines showing portions of the remote control is for illustrative purposes only and forms no part of the claimed design.
